DESIGN FOR AN EYE PROTECTOR OR SIMILAR ARTICLE

Daniel P. Bernheim, Southbridge, Mass., assignor to American Optical Company, Southbridge, Mass., a voluntary association of Massachusetts

Application March 19, 1942, Serial No. 106,254

Term of patent 14 years

To all whom it may concern:

Be it known that I, Daniel P. Bernheim, a citizen of the United States, residing at Southbridge, in the county of Worcester and State of Massachusetts, have invented a new, original, and ornamental Design for an Eye Protector, or Similar Article, of which the following is a specification, reference being made to the accompanying drawing, forming a part thereof.

Fig. 1 is an elevational view of the front of an eye protector or similar article showing my new design;

Fig. 2 is a plan view of the complete eye protector; and

Fig. 3 is a side elevational view.

The head strap has been shown in fragmentary condition in Figs. 1 and 3 for convenience of illustration.

I claim:

The ornamental design for an eye protector or similar article, substantially as shown and described.

DANIEL P. BERNHEIM.
